Primary Examiner — Dana Meyrow(74) *Attorney, Agent, or Firm* — Santosh K. Chari; Blake, Cassels & Graydon LLP(57) **CLAIM**

The ornamental design for a bottle, substantially as shown and described.

DESCRIPTION

FIG. 1 is a side elevation view of a bottle according to a first embodiment.

FIG. 2 is a top view of the design of FIG. 1.

FIG. 3 is a bottom view of the design of FIG. 1.

FIG. 4 is a perspective view of the design of FIG. 1.

FIG. 5 is a side elevation view of a bottle according to a second embodiment.

FIG. 6 is a top view of the design of FIG. 5.

FIG. 7 is a bottom view of the design of FIG. 5.

FIG. 8 is a perspective view of the design of FIG. 5.

FIG. 9 is a side elevation view of a bottle according to a third embodiment.

FIG. 10 is a top view of the design of FIG. 9.

FIG. 11 is a bottom view of the design of FIG. 9; and, FIG. 12 is a perspective view of the design of FIG. 9.

The portions of the figures shown in broken lines represent features that do not form part of the claimed design.

The shading shown in the figures serves to illustrate contour and is not surface ornamentation.
